LUBRICATING DEVICE FOR TWISTER.
RINGS

William O. Aldrich, Whitinsville, and Fred K. Hendrickson, Worcester, Mass., assignors to Whitin Machine Works, Whitinsville, Mass., a corporation of Massachusetts

Application July 3, 1933, Serial No. 678,908

4 Claims. (Cl. 118—59)

This invention relates to twisting machines of the ring type, particularly designed for twisting relatively heavy thread or yarn. In such machines, the excessive pull on the traveler renders lubrication of the rings desirable to reduce traveler wear and replacement. It is also necessary to prevent excess oil from collecting on the floor below the machine.

It is the general object of our invention to provide an improved and simplified construction by which a twister ring may be effectively lubricated and by which excess oil will be collected and transferred to a suitable receptacle.

A further object of our invention is to provide a construction of lubricating device which may be readily installed in existing frames without expensive alteration thereof.

Our invention further relates to arrangements and combinations of parts which will be herein-after described and more particularly pointed out in the appended claims.

A preferred form of the invention is shown in the drawing, in which

Fig. 1 is a plan view of a portion of a ring rail having our invention applied thereto;

Fig. 2 is a transverse sectional elevation, taken along the line 2—2 in Fig. 1;

Fig. 3 is an enlarged detail sectional elevation, taken along the line 3—3 in Fig. 1, and

Fig. 4 is a partial plan view of the oil receptacle and ring, with portions of the ring shown in section.

Referring to the drawing, the usual ring rail 10 is provided with circular openings 11 in which we secure substantially cylindrical ring holders 12 in any convenient manner, as by set-screws 13.

A twister ring 20 is provided with a flange 21 projecting outwardly therefrom, and the ring 20 is preferably mounted in the holder 12 by forcing the ring into the cylindrical upper portion of the holder 12 until the shoulder 21 engages the top surface of the holder.

The lower portion of the holder 12 is flanged inwardly and upwardly as indicated at 22 to provide an annular channel or recess 23 in which oil dripping from the traveler T or from the lower edge of the ring 20 will be collected.

At one side of each ring holder there is provided a vent or short spout 24, positioned above a conductor 25 extending lengthwise of the ring rail and adapted to convey excess oil to a suitable receptacle located at any convenient point. The conductor 25 preferably has an upwardly extending flange portion 26 adapted to be secured to the side of the ring rail 10 by screws 27.

An oil receptacle 30 surrounds the upper portion of the ring holder 12 and is preferably permanently assembled therewith by forcing the receptacle 30 over the upper end of the holder 12 or by welding or otherwise securing these parts in assembled relation.

The bottom of the receptacle 30 forms a shoulder when the parts are assembled, by which shoulder the holder 12 is vertically positioned in the ring rail 10.

The ring 20 is provided with radial openings 32 (Fig. 4) communicating with a slot 33 on the inner face of the ring, said radial openings extending outward through the flange 21. A wick W is threaded through the openings 32 and along the slot 33 and may be knotted at the outer side of the ring as indicated in Fig. 4.

The ends of the wick W extend to a greater or less extent around the outside of the ring holder 12 and are received in the oil receptacle 30 which by reason of its annular form is capable of holding a considerable supply of oil.

A cover plate 40 fits inside of the receptacle 30 and outside of the ring flange 21 and excludes dirt and other foreign matter from the oil in said receptacle. An opening 41 is provided for supplying oil to the receptacle 30, and a portion 42 of the plate 40 is bent upward to clear the wick W where it enters the radial passages 32 and to form a shield thereover.

The slot 33 is preferably so located in the face of the ring 20 that it is slightly above the point of bearing engagement of the traveler T with the inner face of the ring 20.

Having described the details of construction of our improved lubricating device, the use and advantages thereof will be readily apparent. The receptacle 30 holds a supply of clean oil from which dirt and lint is excluded by the cover 40. This oil is drawn upward by the capillary action of the wick W and is transferred in minute quantities to the slot 33 in the inner surface of the ring 20, from which slot it oozes downward to lubricate the traveler.

Any excess of oil dripping from the traveler or from the lower edge of the ring will be collected in the channel 23 of the holder 12, from which channel it will flow to the conductor 25, to be thereafter delivered to a collecting or storage receptacle. The oil thus collected may be filtered or otherwise purified and used again if so desired.

It will be noted that the ring 20, ring holder 12, receptacle 30 and wick W may be assembled and handled as a unit and may be inserted in

and removed from the rail 10 as a separate unitary structure.

All parts are simple and easily constructed, and the advantages of our invention may be utilized at very slight increase in cost over the ordinary construction in which manual lubrication is commonly necessary.

Having thus described our invention and the advantages thereof, we do not wish to be limited to the details herein disclosed, otherwise than as set forth in the claims, but what we claim is:—

1. In a ring twisting machine having a ring rail with a circular ring aperture, in combination, a vertical-flange twister ring, a ring holder therefor snugly fitting the aperture in said ring rail and having an annular oil-collecting channel in its lower portion, and means to supply oil to said ring, said ring, ring holder and oil supply means forming a separately assembled unitary structure.
- 15 2. In a ring twisting machine having a ring rail with a circular ring aperture, in combination, a vertical-flange twister ring, a substantially cylindrical ring holder therefor snugly fitting the aperture in said ring rail and having an inwardly and upwardly projecting flange at its lower edge forming an annular oil-collecting channel, and means to supply oil to said ring, said ring, ring holder and oil supply means forming a separately assembled unitary structure.
- 25 3. In a ring twisting machine having a ring

5 rail with a circular ring aperture, in combination, a vertical-flange twister ring, a ring holder therefor snugly fitting the aperture in said ring rail and having an annular oil-collecting channel in its lower portion, a substantially annular oil receptacle mounted on the upper part of said holder and providing an external shoulder to engage the ring rail and vertically position said ring holder, and a wick extending from said receptacle through radial openings in the ring to the inner face thereof, said ring, ring holder and oil receptacle forming a separately assembled unitary structure.

10 4. In a ring twisting machine having an apertured ring rail, in combination, a vertical-flange 15 twister ring, a ring holder therefor having an annular oil-collecting channel in its lower portion, a substantially annular oil receptacle mounted on the upper part of said holder and providing an external shoulder to engage the ring 20 rail and vertically position the ring holder, a wick extending from said receptacle through radial openings in the ring to the inner face thereof, and a cover for said receptacle fitting between said ring and the outer wall of said receptacle 25 and effectively excluding dirt from said receptacle, said cover having an oil opening at one part thereof and having an upwardly displaced portion shielding the wick at another part.
